UNITED STATES PATENT OFFICE.

WILLIAM F. RAY, OF CHICAGO, ILLINOIS.

CORE OR MANDREL.

1,250,504.

Specification of Letters Patent. Patented Dec. 18, 1917.

Application filed July 20, 1917. Serial No. 181,693.

To all whom it may concern:

Be it known that I, WILLIAM F. RAY, a citizen of the United States, residing at Chicago, in the county of Cook and State of Illinois, have invented a new and useful Improvement in Cores or Mandrels, of which the following is a specification.

This invention relates particularly to annular cores or mandrels adapted for use in the manufacture of pneumatic tires or linings for same.

The primary object of the invention is to provide a sectionally constructed annular core which is simple, cheap and durable and which can be removed with great facility from the tire or interliner after the carcass has been built upon the core and the vulcanizing operation effected.

The invention is illustrated in its preferred embodiment in the accompanying drawing, in which—

Figure 1 represents a plan view of a sectionally constructed core embodying my invention; Fig. 2, a broken perspective view showing one extremity of the main section of the core; Fig. 3, a broken perspective view showing one end of the detachable core-section and the locking means with which it is equipped; and Fig. 4, a broken sectional view illustrating the manner in which the extremities of the removable or minor section of the core is interlockingly engaged with the major section of the core.

In the construction illustrated, A represents the major section of the improved annular core or mandrel; and A¹, the detachable minor section.

The core-sections are preferably formed of cast metal, machined to present the desired cross-sectional contour.

The core illustrated is of proper design for use in the manufacture of interliners for tires. Preferably, the main or major section A is of integral formation and comprises two-thirds or more of the annulus. Each extremity of the member A is provided with plane surfaces 1 and 2 which are offset with relation to each other or lie in different planes, which, however, may be parallel planes. These surfaces are intersected by a plane surface 3 forming an acute angle with each of the planes 1 and 2, thus providing an undercut or notch 4; that is, each extremity of the main core-section A is provided with a reentrant angle, indicated at 4.

As indicated in Fig. 1, the planes of the surfaces 1 converge somewhat in an outward direction; and the same is true of the planes of the surfaces 2, the purpose being to enable the detachable section A¹ to easily and quickly free itself when said section is moved inwardly to a position indicated by dotted lines in Fig. 1. At a median point, guide tenons 5 are provided on the surfaces 1 of the main core-section; and, further inwardly, the surfaces 2 are provided with sockets 6 adapted to receive the locking pins with which the detachable section A¹ is equipped.

The relatively small core-section A¹ is provided with surfaces 1^a and 2^a which are complementary to, or correspond with the surfaces 1 and 2 of the main section; and the surfaces 1^a and 2^a are intersected by a surface 3^a which is complementary to the surface 3. As thus described, the extremities of the section A¹ are provided with angular projections 4^a which are adapted to fit accurately into the recesses or notches 4. The surfaces 1^a are provided with guide grooves 5^a which are adapted to receive the guide tenons 5.

The minor section A¹ is equipped with slideable locking pins 6^a which are adapted to enter the sockets 6. The pins 6^a are slideable in guides 7 which are preferably substantially perpendicular to the radii of the annulus and which guides open at the center portion of the surfaces 2^a. The locking studs 6^a may be manipulated by means of radial projections 8 whose inner ends are firmly secured to the locking studs. The lugs or projections 8 are adapted to work in radial slots 9 which intersect the guides 7.

In the use of the improved core, the detachable section A¹ is firmly secured in the position indicated by the full lines in Fig. 1 and as shown in the sectional view in Fig. 4. The carcass of the interliner is built upon the core or mandrel in the usual manner, it being usual to have the edges of the fabric, or certain plies of the fabric, entering into the construction of the interliner, extend flush with the lines 10 at the inner circumference of the core. After the vulcanizing operation, the locking studs 6^a may be disengaged from the socket 6 by tapping upon the lugs 8 which project through the slot at the inner circumference of the interliner. When this is effected, the section A¹ may be tapped inwardly and removed

from the interliner, after which the interliner may be readily stripped from the main section of the core. It is to be observed that the improved core preferably comprises 5 only two sections, and the extremities of the two core-sections are so interlocked as to mutually brace each other against expansion of the annulus. This results from the undercut notches and projections employed 10 at the meeting extremities of the core-sections, and is supplemented by the disposition of the locking studs 6^a and the manner in which they enter the sockets 6.

The construction described is simple, 15 cheap, thoroughly durable and easily manipulated. It may be noted, also, that the construction provides an unobstructed or substantially continuous inner surface for the core or mandrel, so that the mandrel 20 may be readily secured upon a suitable tripod or base to facilitate the operation of building up the carcass upon the core.

The foregoing detailed description has been given for clearness of understanding 25 only and no unnecessary limitation should be understood therefrom, but the appended claims should be construed as broadly as is permissible in view of the prior art.

What I regard as new and desire to secure 30 by Letters Patent is—

1. An annular core comprising two sections only, one of said sections being relatively short, said sections having extremities provided with offset surfaces which converge somewhat outwardly and intersecting 35 surfaces forming interlock notches adapted to resist expansion of the core and substantially tangentially slidably locking studs connecting the extremities of the sections.

40 2. An annular core comprising two sec-

tions only, one section being a relatively short section, said sections being provided with surfaces offset from each other and converging outwardly, said surfaces being intersected by surfaces forming interlock notches, and a pair of substantially tangentially slidably locking studs carried by the smaller section and having extremities adapted to be projected into locking engagement with the ends of the other section. 50

3. An annular core comprising a main section, each of whose extremities is provided with a pair of surfaces which are offset from each other and intersected by a connecting surface, the upper or outer surface being equipped with a guide tenon and the inner surface being equipped with a socket, and a complemental smaller section having surfaces corresponding with said first-named surfaces and provided with 55 guide grooves, said smaller section being equipped with tangentially movable locking devices adapted to engage the sockets in the extremities of the main section.

4. An annular core, comprising a short 65 section having plane end-surfaces which are offset and convergent and having also intersecting plane surfaces forming interlock notches, a complemental annulus portion having corresponding convergent offset 70 plane surfaces and intersecting plane surfaces forming interlock notches, tenon and groove connections between said surfaces, and substantially tangentially movable locking bolts mounted in guides open at the ends 75 of said short sections and having actuating lugs movable in slots opening at the inner circumferential surface of said short section.

WILLIAM F. RAY.
